UNITED STATES PATENT OFFICE.

ROBERT L. BOYTER, OF LAKEVIEW, TEXAS

TIE-WIRE FOR INSULATORS.

1,215,245.

Specification of Letters Patent. Patented Feb. 6, 1917.

Application filed August 28, 1916. Serial No. 117,322.

To all whom it may concern:

Be it known that I, ROBERT L. BOYTER, a citizen of the United States, residing at Lakeview, in the county of Hall and State of Texas, have invented new and useful Improvements in Tie-Wires for Insulators, of which the following is a specification.

This invention relates to improvements in attaching devices for connecting electric current carrying wires to insulators.

In carrying out the present invention, it is my purpose to provide a device of the class described whereby the wire may be fastened to the insulator without the necessity of employing tie wires and the like, and which may be attached to the wire and to the insulator quickly and conveniently.

It is also my purpose to provide a device of the type set forth which will embrace the desired features of simplicity, efficiency and durability, and which may be manufactured and marketed at small cost.

Another object of my invention is the provision of an attaching device for fastening electric current carrying wires to insulators which will be held on the insulator by the current carrying wire, the device being so constructed as to clamp the insulator under the action of the wire to which it is connected.

With the above and other objects in view, the invention consists in the construction, combination and arrangement of parts hereinafter set forth in and falling within the scope of the claim.

In the accompanying drawing;

Figure 1 is a view in side elevation of an insulator and an electric current carrying wire connected to the insulator by means of an attaching device constructed in accordance with the present invention.

Fig. 2 is a horizontal sectional view through the insulator showing the attaching device in top plan.

Fig. 3 is a perspective view of the attaching device removed from the insulator.

Referring now to the drawing in detail, 1 designates an insulator constructed of glass, porcelain or other suitable material and formed with a longitudinal bore 2 through which the securing bolt is adapted to pass, and with a circumferential groove 3. My improved attaching device is indicated at 4 and comprises complementary sections 5, 5 each stamped from a single piece

of metal formed to provide a base 6 having one edge curved to conform to the curvature of the insulator and formed on the curved edge of the base adjacent to one end thereof is an outwardly projecting lug 7 having the inner edge formed with an overlying hook 8. Formed on the base adjacent to the opposite end thereof is an overlying hook 9 turned in a direction reverse to the hook 8. Formed integral with the base 6 at a point 65 behind the hooks 8 and 9 is a strap 10 twisted to a position at right angles to the base so as to fit nicely into the groove 3. The outer ends of the strap 10 on the complementary sections are formed with an outwardly projecting lug 11 and opening 12 respectively, the opening being adapted to receive the lug 11 when the sections are assembled.

In practice, the wire is trained through the oppositely disposed hooks 8 and 9 on the respective sections of the device and bent slightly around the insulator with the thumb and forefinger so that the strap with the opening 12 will overlie the strap with the lug 11. The wire is then pulled back to normal position and the lug 11 drops into the opening 12, thereby locking the device upon the insulator. As the wire is tightened, the portion thereof within the hooks 8 and 85 9 tends to straighten out, thereby causing the sections to bind upon the insulator.

While I have herein shown and described the preferred form of my invention by way of illustration, I wish it to be understood that I do not limit or confine myself to the precise details of construction herein described and delineated, as modification and variation may be made within the scope of the claim and without departing from the spirit of the invention.

I claim:

The combination with a supporting insulator, and an electric current carrying conductor, of an attaching device for holding the conductor to the insulator embodying complementary sections each formed from a single piece of metal formed to provide a base having one section curved to conform to the curvature of the insulator, an outwardly projecting lug formed on the inner edge of the base adjacent to one end thereof, an overlying hook on said lug, a second hook on said base adjacent to the other end thereof and turned in a direction reverse to 110

the first mentioned hook and overlying said base, straps integral with said base members respectively, and each twisted to a position at right angles to the base and adapted to fit into a groove in the insulator, the outer ends of said straps being formed to interlock, and said insulators being adapted

to receive said conductor and coöperating with the interlocking straps to hold the device on the insulator and secure the conductor to the insulator. 10

In testimony whereof I affix my signature.

ROBERT L. BOYTER.
